TOBACCO PIPE

Charles W. Pepper, Denver, Colo.

Application March 26, 1949, Serial No. 1,630

Term of patent 14 years

(Cl. D85—8)

To all whom it may concern:

Be it known that I, Charles W. Pepper, a citizen of the United States, residing in the city and county of Denver, have invented a new, original, and ornamental Design for Tobacco Pipes, of which the following is a specification, reference being had to the accompanying drawing, forming part thereof in which the dominant features are shown in full lines.

I claim:

The ornamental design for a tobacco pipe, as shown and described.

CHARLES W. PEPPER.
